DESCRIPTION

FIG. 1 is a perspective view of a display bracket for use with mounting systems for audio/visual devices or the like showing my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof, the bottom plan view being identical to the top plan view.
